UNITED STATES PATENT OFFICE.

CHARLES A. KUTCHER, OF SHERIDAN, WYOMING.

EYELETING-MACHINE.

1,208,581.

Specification of Letters Patent. Patented Dec. 12, 1916.

Application filed August 11, 1916. Serial No. 114,445.

To all whom it may concern:

Be it known that I, CHARLES A. KUTCHER, a citizen of the United States, residing at Sheridan, in the county of Sheridan and 5 State of Wyoming, have invented certain new and useful Improvements in Eyeletting-Machines; and I do declare the following to be a full, clear, and exact description of the invention, such as will enable others 10 skilled in the art to which it appertains to make and use the same.

This invention relates to improvements in eyeletting machines which are provided with means for automatically feeding the 15 eyelets to the eyelet setters.

The principal object of the present invention is to provide a machine of this character so constructed that when its operating handle is depressed to punch a hole in the 20 articles to be fastened, the automatic feeder is brought into position to have one of its eyelets removed by the eyelet setting plunger, when the handle is released, and when the handle is raised the eyelet caught by 25 the plunger will be crimped in the hole formed by the punch.

An additional object is to provide a machine having means for disengaging the automatic eyelet feed so as to permit the de- 30 vice to be used merely as a punch.

Still another object is to provide a simply constructed machine having its parts arranged in a new and improved relation to accomplish more efficient results.

With these and other objects in view, the 35 invention resides in the novel features of construction, combination and arrangement of parts which will be later described and claimed and shown in the drawings wherein:

Figure 1 is a side elevation of a machine constructed in accordance with this invention, the parts of which are in their normal positions, some of them being broken away and shown in section; Fig. 2 is a similar 40 view showing the position of the parts during the punching operation; Fig. 3 is a similar view showing the position of the parts when clamping a number of sheets together; Fig. 4 is a side elevation of the opposite side 45 of the device, some of the parts being broken away and in section; Fig. 5 is a horizontal sectional view taken on the line 5—5 of Fig. 1; Fig. 6 is a similar view taken on the line 50 6—6 of Fig. 2; Fig. 7 is a perspective view 55 of the completed machine; Fig. 8 is a perspective view of the discharge end of the

eyelet runway; Fig. 9 is a perspective view of the spring for holding the eyelets in the runway; Fig. 10 is a detail vertical sectional view showing the plunger in the act of 60 clamping several sheets of paper; Fig. 11 is a similar view of the eyelet carrying plunger; and Fig. 12 is a detail vertical sectional view through the eyelet runway.

Referring more particularly to the several 65 figures of the drawings wherein similar reference characters indicate like parts, 1 designates the frame upon which the operating mechanism is mounted, said frame consisting of a hollow base 2 having a separable top 3 70 with which an upright supporting member 4 is integrally united, said last mentioned portion being approximately triangular in shape and about one-half inch more or less in thickness.

75 Formed integrally with the upright straight edge of the portion 4 is a rectangular block 5 which is also integrally connected to the top 3, while disposed over said block and similarly connected to said straight upright edge is a substantially rectangular anvil 6. This member 4 and the part 3 upon which it is mounted together with the block 5 and anvil 6 are preferably cast in one piece so as to produce a strong yet com- 80 paratively light frame.

85 Formed vertically through the anvil 6 adjacent one edge thereof is a bore 7 in which a cylindrical punch 8 is reciprocally mounted. The lower or active end of this 90 punch 8 is reduced as shown at 9 and adapted to be disposed in an aperture 10 when the former is depressed. This aperture 10 is formed vertically in the block 5 and extends partially therethrough, its lower end com- 95 municating with a discharge opening 11 which provides an exit for the punchings. The upper end of the punch 8 is bifurcated and receives a link 12, said link being pivoted thereto and between the ears 13 which 100 are formed on the under side of an operating lever or handle 14. The latter has an enlarged bifurcated head 15 formed at one end between the furcations of which the upper end of the member 4 is disposed. Said head 105 is pivoted to the member 4 adjacent the straight edge of the latter by means of the pivot pin or screw 16. One of the furcations of the head 15 has a rather long finger 17 formed integrally therewith, the finger 110 having an eye 18 formed in its free end for the reception of one end of a helical con-

tracting spring 19, the other end of which is connected to an eye 20 which is formed on the top 3 of the base. The handle 14 also has an L-shaped member 21 connected thereto, by means of a link 22. The upright arm 23 of the member 21, which is considerably longer than the arm 24 is disposed in a vertical guide formed through the block 5 and anvil 6 adjacent their connections with the portion 4. Said guide which is in the form of an opening also extends through the top 3 of the base 2 and into the latter, where the short arm 24 is disposed beneath the block 5. The free end of this short arm 24 terminates directly below a vertical opening 25 formed through the block 5 and has connected thereto an upright plunger 26 which forms the movable portion of the eyelet set. It will be noted that the plunger 26 is disposed substantially parallel to the long arm 23 and while not nearly so long as the latter, extends up into the block 5, and movable pin 27 extending above the top thereof. This pin 27 is slidably disposed in a socket formed in the end of the plunger 26 and is normally held outwardly by means of an extension spring 28. This pin is adapted to receive and hold in position an eyelet when the machine is about to be used to set an eyelet in one or more sheets of paper or the like.

With the structure thus far described it will be seen that when the sheets of paper which are to be fixed together are placed between the block 5 and the anvil 6 and the operating handle depressed against the tension of the spring 19, the active end 9 of the punch 8 will perforate the paper so that the eyelet may be readily disposed through the several sheets. This down stroke of the lever 14 also causes the pin 27 of the plunger 26 to be lowered below the top of the block 5 so that it does not interfere with the placing of the paper between the latter and the anvil. Assuming that an eyelet has been placed on the pin 27 the paper after being punched is moved toward the left so as to dispose the perforation which has been formed over the pin and the eyelet thereon, whereupon the handle 14 is raised, thus moving the plunger toward the anvil 6 which carries the other portion 29 of the eyelet set. Continued upward movement of the handle clamps the eyelet between the end of the plunger and the portion 29 and sets it in proper position in the paper. It will be noted that as soon as the eyelet comes in contact with the anvil 6 the pin 27 is depressed until its end is flush with the end of the plunger. To facilitate the disposal of the paper between the block 5 and anvil 6 and to hold the edges parallel a suitable paper guide 30 is attached to the portion 4 between said block and anvil. This guide consists of a strip, one portion of which is disposed between the block and anvil at the rear edge thereof, while the outer

portion is secured to said portion 4 by rivets or the like.

As hereinbefore mentioned the machine is equipped with the means for automatically feeding the eyelets to the plunger. This feeding mechanism consists of a raceway 31 which is pivoted to the portion 4 and designed to move into and out of a slot 32 which is formed horizontally through the block 5 and intersecting the vertical opening 25. The raceway 31 has a T-shaped channel extending throughout its length, and is constructed of a base plate 33 of suitable width, to the outer edges of which are secured a pair of spacing strips 34, the latter carrying the flange strips 35. Secured to the opposite sides of the raceway 31, preferably to the strips 35 is a pair of right angular arms 36 which project upwardly and have disposed therebetween one portion of an offset member 37, the other portion of which is pivoted by a screw 38 to the part 4. The raceway is so pivoted by means of its arms 36 and the member 37 and is so curved that a spring 39 connected thereto and the top 3 of the base 2 will readily force its lower end into the slot 32 whenever a stop which will later be described, is removed.

The feeding mechanism is moved out of the way of the other parts when the operating handle 14 is raised in order to set an eyelet. This is accomplished by means of a finger 40 which is carried by the offset member 37 and a shoulder 41 which engages it, said shoulder being formed by notching one of the furcations of the head 15 as shown at 42. The position of the parts as they will appear when the operating handle 14 is raised is shown in Fig. 3. When, however, the handle 14 is released the springs 19 and 39 return all of the parts of the machine into position so that a new eyelet may be set. As the inverted T-shaped channel which is formed in the raceway 31 is the same size throughout its length a suitable retaining spring 43 is disposed at the lower end thereof in order to prevent the eyelets from slipping from the feeder by gravity. This spring 43 is substantially U-shaped and its arms 44 adjacent their connection with the cross bar 45 are disposed in diagonal notches 46. The arms 44 have a tendency to spring toward each other and therefore the spring is readily held in operative position with the arms overlying the top of the lower end of the raceway. The free ends of the arms are curved inwardly toward each other so that it is necessary to forcibly pull each eyelet therebetween when removing it from the channel.

As previously pointed out the plunger 26 is lowered when the operating handle is forced downwardly. This downward movement of the plunger and the L-shaped member 21 which connects it with the handle 14

also causes a stop 47 to be lowered. This rod is reciprocally mounted in an aperture formed in the top 3 of the base 2 and into the block 5 where it communicates with the 5 slot 32. The upper end of the rod projects into said slot 32 and prevents the end of the raceway 31 from fully entering said slot. The rod is normally held in raised position by means of a spring 48 secured to 10 the under side of the top 3 by means of a clamping screw and nut 49, one end of said spring being disposed in a transverse opening formed in the lower portion of said rod. This rod is forced to move downwardly 15 against the tension of the spring by means of a pin 50 which it carries on its lower end for engagement by the arm 24 of the member 21.

The operation of the device is as follows: 20 Assuming that the raceway of the feeder is loaded with several eyelets the several sheets of paper which are to be clamped together are placed between the block 5 and anvil 6 and punched as hereinbefore described. Downward movement of the operating handle for operating the punch has also caused the plunger 26 to be lowered, thereby causing the stop rod 47 to move downwardly, which movement allows the 25 lower end of the raceway 31 to fully enter the slot 32 until its outermost eyelet is directly over the pin 27 of the plunger 26. The spring 39 causes this movement of the raceway as soon as the stop 47 is removed. 30 When, however, the handle 14 is released the spring 19 causes it to move back to its former position, thus returning the punch 8 and the plunger 26 to their former positions. The shoulder 41 of the handle 14 35 also engages the finger 40 and moves the feeding mechanism out of the slot beyond the stop rod 47 whose spring 48 causes it to again become active and prevent the movement of the raceway through the slot 32. 40 This simultaneous movement of the plunger 26 and the raceway 31 causes an eyelet 45 to be caught on the pin 27 and held thereon after said raceway is moved beyond the stop rod. The next operation consists in setting 50 the eyelet which has been picked up by the pin 27 in the paper which has been punched. The paper is disposed over the plunger 26 as before mentioned, whereupon the handle is moved upwardly into the position shown 55 in Fig. 3 thus carrying with it the plunger and eyelet and the paper which is to be clamped together. This upward movement clamps the eyelet on the paper, the feeding mechanism being simultaneously moved 60 rearwardly so that it cannot interfere with the clamping operation. After this movement has taken place the machine is ready to be used to fasten another eyelet in the paper, the operations of the several parts 65 being the same as previously set forth.

Another important feature of my invention consists in means for preventing the operation of the automatic feeding mechanism. This consists of a slotted plate 51 which is slidably mounted on the rear face 70 of the anvil 6, a pin or screw 52 projecting from the anvil and through the slot 53 of the plate for this purpose. Between the head of the pin or screw and the plate 51 is a coiled spring 53 for holding said plate in 75 engagement with the anvil at all times. Now, when it is desired to throw the feeding mechanism out of play the operating handle is raised slightly so as to move the lower end of the raceway from beneath the 80 end of the plate 51 so that the latter may be forced downwardly over the rear entrance to the slot 32 as shown by dotted lines in Fig. 3. This arrangement allows the machine to be operated as a punch but prevents 85 the plunger pin 27 from picking eyelets from the raceway so that it is unnecessary to unload the feeding mechanism whenever it is desired to suspend the operation thereof.

I claim as my invention.

1. In an eyeleting machine, a support, an anvil carried thereby, an operating lever pivoted to said support over the anvil, an L-shaped member connected by one arm to said lever, the other arm extending beneath 95 said anvil, and an eyelet setting plunger for coaction with said anvil fixed to the free end of said last mentioned arm and disposed substantially parallel to the first mentioned arm of said member.

2. In an eyeleting machine, a block, a support, an anvil mounted on said support over said block, an operating lever pivoted to said support, an L-shaped member connected by one arm to said lever, the other 105 arm extending beneath said block, an eyelet setting plunger for coaction with said anvil fixed to the free end of said last mentioned arm and disposed substantially parallel to the first mentioned arm, and a punch 110 connected with the lever and movable toward and away from said block, said plunger being movable below the surface of said block when the punch is brought into contact with the latter.

3. In an eyeleting machine, a support, a block connected thereto, said block having a horizontal slot and a vertical opening formed therethrough and intersecting each other, an anvil disposed over said block, an 120 operating lever pivoted to said support, an eyelet setting plunger disposed in said vertical opening and connected to said lever, an eyelet feeder pivoted to the support and adapted to be moved into said slot, and a 125 compressible stop operable by said plunger to prevent said feeder entering said slot.

4. In an eyeleting machine, a support, a block connected thereto, said block having a horizontal slot and a vertical opening 130

an anvil disposed over said block, an operating lever pivoted to said support, an eyelet setting plunger disposed in said vertical opening and connected to said lever, an eyelet feeder pivoted to said support and comprising a raceway, the lower end of said raceway being adapted to enter said horizontal slot, said end of said raceway having its outer sides diagonally notched, and a 5 U-shaped retaining spring disposed over the lower end of said raceway, the arms thereof being disposed in said diagonal notch, the cross arm of said spring engaging the under side of the feeder, the free ends of the arms 10 of said spring being bent inwardly toward each other to aid in retaining eyelets in the raceway.

12. In an eyeleting machine, a support, an anvil, an eyelet setting plunger, means for operating said plunger, an eyelet feeder movable across the path of said plunger, a plate slidable on said anvil into the path of movement of said feeder to prevent the 20 operation thereof, and means for holding 25 said plate in adjusted position.

13. In a device of the class described, an anvil, an eyelet setting plunger, an eyelet feeder movable across the path of movement of said plunger, a vertically movable rod for 30 intersecting the path of said feeder to retain the same in retracted position, a finger on said rod to be engaged by said plunger, and an operating handle for successively depressing said plunger and rod to permit 35 said feeder to move across the path of movement of said plunger.

14. In a device of the class described, an anvil, an L-shaped member having one arm

disposed beneath said anvil, an operating lever having the other arm of said member 40 connected thereto, an eyelet setting plunger carried by the free end of the first mentioned arm of said member, an eyelet feeder movable across the path of movement of said plunger, a vertically movable rod intersecting the path of movement of said feeder to 45 retain the same in retracted position, and a finger on said rod to be engaged by the first mentioned arm of said L-shaped member, said plunger and rod being successively depressed upon operation of said operating lever.

15. In an eyeleting machine, a support, an anvil, an eyelet setting plunger, an eyelet feeder movable across the path of movement 55 of said plunger and comprising a raceway, and an offset member pivoted to said support and to said raceway, a stop to hold said feeder in retracted position, an operating handle for successively depressing said 60 plunger and stop, whereby to permit said raceway to move across the path of movement of said plunger, a shoulder on said operating handle, and a finger on said offset member for engagement by said shoulder to 65 return said feeder to its retracted position after said raceway has passed across the path of movement of said plunger.

In testimony whereof I have hereunto set my hand in the presence of two subscribing 70 witnesses.

CHARLES A. KUTCHER.
